HENRY N. SMITH, OF HOPEDALE, MASSACHUSETTS, ASSIGNOR TO DRAPER CORPORATION, OF HOPEDALE, MASSACHUSETTS, A CORPORATION OF MAINE

BEAM LOCK FOR LOOMS

Application filed March 30, 1931. Serial No. 526,188.

This invention relates to beam locks for looms and is particularly directed to a simple and effective means readily operable to lock and unlock the beam in its bearings.

5 When the warp beam is supplied with yarn and is supported in its bearings there is not only considerable wear on the journals or gudgeons, but the vibration of the loom is liable at times to disturb the locked condition of the beam, so that the latter may jump or give under the shedding and beat-up movements of the loom, with the result that imperfect cloth may be woven.

10 It is now the common practice to provide beam locks for looms but in most instances the locking mechanism has been of a complicated nature and in many instances unreliable, and requiring more than a single manipulation of the loom attendant to lock and unlock the beam.

15 One of the objects of the present invention is to provide a beam lock for looms which shall be simple in construction and effective in operation, and readily manipulated and adjusted to lock the beam in its operating position.

20 Another feature of the invention consists in providing a safety catch for holding the locking means in locking position notwithstanding vibrations in the loom itself.

25 The invention and novel features thereof will best be made clear from the following description and accompanying drawings of one good practical form thereof.

30 In the drawings:—

Fig. 1 is a side elevation of a loom containing the present invention, some of the parts being broken away;

35 Fig. 2 is a sectional side elevation on the line 2—2 of Fig. 3 showing the beam lock in locked position;

40 Fig. 3 is a rear view showing the beam and the beam lock at each end thereof;

45 Fig. 4 is an enlarged detached view show-

ing one of the beam locks being moved into locking position; and

Fig. 5 is an enlarged section on the line 5—5 of Fig. 2.

50 It will be understood, of course, that the beam is provided with a lock at each end thereof, and since such locks may be of the same general construction a description of one will be sufficient.

The loom frame 1 may be of usual construction, and above the warp beam it is provided with the usual guides or whip rolls 2 and 3, over which the warp threads pass to the weaving instrumentalities.

55 Open journaled bearings are provided at each side at the rear of the loom for the support of the journals or gudgeons of the warp beam, and as shown in the present instance of the invention such bearings 4 are provided on a bracket 5, which may be supported in position on the loom frame by the securing bolts 6.

60 As shown, the brackets 5 are also provided with additional seats 7 for facilitating the manipulation of the warp beam in placing it in and taking it out of its locked position. It may be desirable at times to provide for adjustment of the brackets and to this end they are each provided with slots 8, best shown in Fig. 4, whereby loosening of the 65 securing bolts 6 may permit adjustment of the brackets 5 within desired limits.

70 The warp beam 9 is provided with the usual journals or gudgeons 10, which may be received in the open bearings 4, as indicated in Fig. 4, and in case the warp beam 9 is to be positively operated it may be provided with a pinion 11 adjacent one head thereof to cooperate with the usual positive let-off mechanism, but since these details form no essential part of the present invention they are not herein further illustrated and described.

75 In accordance with the present invention the beam lock is under the control of a single manually operable locking lever pivotally 80

connected to the loom frame or the bracket 5, as shown. The locking lever 12 in the present instance of the invention is pivotally mounted on a stud or pin 13 for pivotal movement thereon, and such stud or pin is eccentrically mounted on a head portion 14 in the bracket 5. As a convenient means for varying the pivotal point of the locking lever 12 the head portion 14 is provided with a groove 15, by which the combined pin and its head support may be conveniently turned to vary the position of the pivot of the locking lever.

Pivotally mounted on the locking lever 12 between the ends thereof, as at 16, is the journal retainer 17, the upper portion of which is provided with a rounded seat 18 to embrace the journal or gudgeon of the beam and close the open bearing when the parts are in beam locking position.

20 The journal retainer 17 has a laterally extending portion 19 forming a recess on the front face of the journal retainer to permit the pivotal connection 16 between it and the locking lever to be moved laterally beyond a line passing through the axis of the beam gudgeon or journal and the pivot 13 of the locking lever, as indicated in Fig. 2, the result being that when the locking lever 12 has been moved into locking position the pivot 16 will take a locking position frontward of the line *a*—*b* of Fig. 2, passing through the axis of the beam gudgeon or journal and the pivot 13 of the locking lever, thereby effectively locking the parts in operative position.

Notwithstanding the locked position of the locking lever and pivot connection 16 between it and the journal retainer 17, it may happen at times that the vibration of the loom or accidental contact of the locking lever by some moving object will cause the lock to pass into an unlocked position, or at least, release the gudgeon or journals of the beam, and to overcome this difficulty the present invention contemplates in addition to the means already described, the provision of a safety catch which shall act to hold the parts in their locking position until the catch is intentionally released.

50 In the present instance of the invention the locking lever 12 has a head portion or hub 20 which is provided with a tooth or shoulder 21 and the journal retainer is provided with a pivoted cooperating member 22 having a tooth or shoulder 23 to engage the tooth or shoulder 21 of the locking lever when the parts are in locked position, as indicated in Fig. 2.

With the parts in unlocked position, as indicated in Fig. 4, the locking lever 12 may be turned about its pivotal support in a contra-clockwise direction as shown in said figure, and if at this time the upper portion of the journal retainer has been moved over the gudgeon or journal of the beam, it will be

drawn downwardly as the locking lever is swung to locking position until the pivotal connection 16 between the locking lever and journal retainer has been moved beyond a line such as *a*—*b* of Fig. 2, passing through the axis of the gudgeon or journal and the axis of the pivot 13, the result being that the parts are then locked and no jumping movement of the warp beam in an upward direction can disturb the locked condition.

70 The safety catch hereinbefore described is of the automatic gravity type, so that when the locking lever 12 has been moved into locking position, as indicated in Fig. 2, the pivotal member 22 of the safety catch will drop automatically into engagement with its cooperating member 21 on the locking lever. When the parts are in the position stated and as shown in Fig. 2, the vibration of the loom or any accidental contact of the locking lever with a moving object will have no effect in disturbing the locked condition of the beam, because at this time the safety catch is operating and will prevent any movement of the locking lever 12.

75 In order that the amplitude of movement of the locking lever 12 shall be only such as to carry the pivot 16 beyond the line *a*—*b* of Fig. 2, the forward face of the journal retainer 17 is caused to bear upon the hub portion 20 of the locking lever, as indicated in Fig. 2.

80 From the construction described, it will be apparent that the beam lock is self-locking when the locking lever 12 is thrown into locking position, as at this time the safety catch becomes effective. Moreover the beam may be freed from its lock by manually lifting the pivoted member 22 of the safety catch, thereby permitting the locking lever 12 to be moved to unlocking position.

85 During weaving there will necessarily be some wear between the gudgeons or journals of the beam, and its bearings, and should this occur the head 14 of the eccentrically mounted pivot pin 13 may be turned by an ordinary screw driver while the loom continues to run and thereby all wear may be taken up.

90 When the beam has been unlocked and removed from the loom it is desirable that the journal retainer shall not project rearwardly from the loom in position to be injured by contact with a moving object and so the journal retainer is provided with an inclined shoulder 24, which may engage a reversely inclined surface on the journal bearing when the beam is out, so that while the parts may not be moved into locking position as hereinbefore described the journal retainer may be held in convenient position out of the path of any moving objects at the rear of the loom.

95 What is claimed is:—

100 A beam lock for looms, comprising an open journal bearing, a journal retainer for closing

the bearing, a manually operable lever pivotally connected to the loom frame, a pivotal connection between the journal retainer and said lever at a point between the ends of the lever so that when the lever is turned about its pivotal support it will draw the journal retainer lengthwise to close the open bearing and move the pivotal connection into locking position, and a safety catch, the members of which are mounted one on the lever and the other on the journal retainer to hold the parts in journal locking position.

In testimony whereof, I have signed my name to this specification.

15

HENRY N. SMITH.
